UNITED STATES PATENT OFFICE.

GEORGE CORMACK, JR., AND FREDERICK C. ZUMDAHL, OF ROCKFORD,
ILLINOIS.

MEANS FOR CONTROLLING THE VALVES FOR EXPLOSIVE-ENGINES.

No. 846,780.

Specification of Letters Patent.

Patented March 12, 1907.

Application filed February 5, 1904. Serial No. 192,104.

To all whom it may concern:

Be it known that we, GEORGE CORMACK, Jr., and FREDERICK C. ZUMDAHL, citizens of the United States, residing at Rockford, in the county of Winnebago and State of Illinois, have invented certain new and useful Means for Controlling the Valves for Explosive-Engines, of which the following is a specification.

10 The object of this construction is to exert additional spring force on the inlet-valve while the exhaust-valve is open.

In the accompanying drawings, Figure 1 is a vertical section on dotted line *a*, Fig. 2. Fig. 2 is a vertical section on dotted line *b*, Fig. 1. Fig. 3 is a section of the spring arrangement controlling the inlet-valve, the valve held normally closed. Fig. 4 is a similar section to Fig. 3, in which additional 20 spring-pressure is brought to bear upon the inlet-valve at the time the exhaust-valve is held open.

From the cylinder 1 extends a passage-way 2, leading to the valve-seat openings 3 and 4, the former communicating with a horizontal chamber 5 and the latter communicating with a passage-way 6, leading to the outer air, known as an "exhaust-opening." A valve 7 is fitted to the seat 3 and has its 30 stem 8 extending upward through the casing. An arm 9 has a movable engagement with the valve-stem. Two coiled springs 10 and 11 surround the valve-stem, and a nut 12 has a screw-thread connection with the upper 35 end of the valve-stem. The inner coiled spring 11 is somewhat shorter than the outer coiled spring 10 for a purpose to appear hereinafter. A valve 13 is fitted to the seat 4 and has a stem 14 extending downward 40 through the casing, and to its lower end is connected an arm 15. A coiled spring 16 surrounds the valve-stem 14 and is located between the arm 15 and casing. A rod 17 extends parallel with the valve-stems 8 and 45 14 and forms a connection between the two arms 9 and 15.

A rocker-arm 18 has a pivotal connection with the cylinder 1, one end supporting a roller 19 and its other end located beneath 50 the end of the valve-stem 14. A cam 20 is supported by the shaft 21 and in its rotations will oscillate the rocker-arm 18, which will move the valve-stem 14 upward and raise the valve 13 from its seat against the

action of the spring 16, thereby allowing the 55 burnt gases to escape from the cylinder through the exhaust-opening 6.

At the time of opening the exhaust-valve 13 the inlet-valve will be held against its seat by the action of the spring 10; but as it is best 60 to employ a light spring to hold the valve 7 against its seat it is necessary that said valve should be held firmly against its seat during the time the exhaust-valve is open. This we accomplish by the connection between the 65 exhaust and inlet valves and the inner coiled spring 11. As the exhaust-valve opens the connection between the valves will be moved, which will raise the arm 9 and raise the spring 11 bodily against the nut 12 and 70 somewhat compresses the spring, thereby imparting greater force to the inlet-valve stem and hold the valve more firmly to its seat.

A spring-arm 22 is supported by the casing, 75 but insulated therefrom, and to it will be connected one of the wires leading to the battery and forming part of the electric circuit employed in exploding the engine. A screw 23 extends from the arm 9, and when 80 the exhaust-valve is closed a contact is made between the spring and screw, thereby closing the circuit, and when the exhaust-valve opens the screw will be carried free of the spring, thereby breaking the circuit. 85

The horizontal chamber 5 opens into an enlarged mixing-chamber 24, and from this mixing-chamber extends a *T* having the vertical passage-way 25 and the horizontal passage-way 26. A check-valve 27 is fitted to 90 a seat 28 in the passage-way 25. A small opening 29 for the supply of gasoline communicates with the seat 28, so that when the check-valve 27 is closed, the supply of gasoline is cut off.

A globe-valve 30 is located in a pipe connection with horizontal passage-way 26.

In starting a gasoline-engine it is necessary that an excess amount of gasoline be used; but as the engine gains in speed the proportion of gasoline to the air may be reduced. This we accomplish by closing the globe-valve 30, thereby compelling all the air to pass the check-valve 27, which will hold it open and allow gasoline to mix with the air 100 and pass onto the cylinder in the usual manner. As the engine gains in speed we open the globe-valve, which will allow the admission 105

of air to the cylinder without passing the check-valve; but the amount of air allowed to pass the globe-valve when mixed with air and gasoline passing the check-valve will be in the proper proportions to give the required results.

The enlarged mixing-chamber 24 forms a space within which the air and gasoline can thoroughly mix before passing to the cylinder.

We claim as our invention—
In a gasoline-engine, the combination of

an exhaust-valve, an inlet-valve, two coiled springs surrounding the stem of the inlet-valve and of different lengths, a connection between the valves, the connection with the inlet-valve being such as to compress both springs only when the exhaust-valve is open. 15
